PALLET HOIST ATTACHMENT

Robert P. Sturgis, Woodbury, N. J., assignor to
Socony-Vacuum Oil Company, Incorporated, a
corporation of New York

Application September 26, 1950, Serial No. 186,749

1 Claim. (Cl. 294—67)

1

This invention relates to a device for attachment to a hoist whereby loaded pallets may be readily handled. The invention is particularly well adapted for use in loading and unloading ship's holds.

During recent years, the use of pallets for handling goods of various kinds has rapidly increased with marked economies in storage and transportation. The technique of using pallets involves loading a predetermined number of packages onto a pallet of wood or steel adapted to be lifted and transported by a fork truck. In the cases of cartons, drums and other relatively rigid elements of regular shape; one loaded pallet may be stacked on another to provide tiers of loaded pallets. Each pallet is readily handled as a unit by fork trucks and a single truck operator is able to handle large quantities of merchandise rapidly with no manual strain.

Due to their small size and short turning radius, fork trucks can handle loaded pallets in restricted spaces, such as ship's holds, railway cars and trucks. Difficulties arise when it becomes necessary to raise or lower loaded pallets in spaces which do not permit of installing suitable ramps. For example, transfer of pallets from a dock to a hold or from a hold to a dock cannot be accomplished by fork truck. The present invention provides a ready mechanism, easily handled by one man, for hoisting loaded pallets.

It is, accordingly, a principal object of the invention to provide means for hoisting loaded pallets which are readily engaged or disengaged from the pallets by simple operations. An outstanding feature of the invention is the relatively small vertical dimension of the device whereby it becomes unnecessary to provide much headroom in excess of the height of a loaded pallet for maneuvering the hoist attachment herein-after described.

These and other objects and advantages of the invention will be apparent from the following description of a specific embodiment of the invention illustrated in the annexed drawings wherein:

Figure 1 is a front elevation of the hoist attachment;

Figure 2 is a fragmentary plan thereof; and

Figure 3 is a side elevation of the attachment.

The hoist attachment comprises a box frame 10 provided at the center with a hook bar 11 to receive the hook of a hoist line. Corner posts 12 are provided at the four corners of the hoist attachment. The two corner posts 12 on one side of the device carry ears 13 pivotally mounted on

2

a shaft 14 extending along the side of the device and rigidly fixed to the box frame 10. The two corner posts 12 on the other side are connected by linkage to be presently described to hinged shafts 15 extending across the top of front and rear portions of the hoist attachment.

Each of the hinged shafts 15 is constructed for hinging on a pivot 16 and each is rigidly fixed at one end to shaft 17, extending along one side of the top of the device. At the other end, each hinged shaft 15 is rigidly fixed to shaft 18 extending along the side of the device opposite to shaft 17. The shafts 17 and 18 are rotatably mounted in ears 19 affixed to the respective corner posts 12. A latch 20 is rotatably mounted on shaft 21 in a latch guide 22. The latch is provided with two recesses adapted to engage a latch pin 23 on the hinged shaft 15. A lever 24 fixed to the shaft 21 is provided for disengaging the latch 20 from the latch pin 23, the weight of the lever 24 holding the latch normally engaged.

Referring specifically to Figure 1, the right front and right rear corners of the box frame 10 carry a release shaft 25 rotatably mounted. At the extremities of release shaft 25 are release cams 26 secured thereto and operated by handles 27. A short link 28 is mounted at one end in the manner shown on release cam 26 for rotation with respect thereto. The other end of short link 28 is rotatably connected to one end of a longer link 29. The other end of longer link 29 is rigidly fixed to shaft 18.

At their bases, corner posts 12 are affixed to an angle iron 30 extending along the sides of the hoist attachment and resting on foot plates 31. Two casters 32 are provided at the front of the device to be used in guiding the same against a wall when hoisting it in a narrow shaftway or other situation in which rotation of the load is undesirable.

It will be apparent that the provision of operating handles 24 and 27 on both front and rear of the device makes it possible to control it from either face. The operation is essentially the same from front or rear. Referring again specifically to Figure 1, the operator pulls up on handle 24, releasing latch 20 from engagement with pin 23. This permits the hinged shaft 15 to "jackknife" about its pivot 16 and such action is caused by moving handle 27 to the right. As the hinged shaft 15 jacks, its effective length is decreased, drawing together the top edges of the two sides and opening the bottom edges. The device is now dropped over a loaded pallet and the handle 27 is moved to the left after release

of the latch 20. This draws the hinged shaft 15 down, pushing out the upper edges and drawing together the angle irons 30 at the bases of corner posts 12 to engage the under surface of the pallet. As the hinged shaft 15 comes into the position shown in Figure 1, the lower recess of latch 20 engages the latch pin 23 rigidly locking the device in engagement with the pallet. The latter may then be hoisted to a desired position and the hoist attachment disengaged by releasing the latch 20 and rotating handle 27 to the right.

I claim:

A hoist attachment comprising a rectangular, horizontal main frame, means at the center of said frame to receive a hoist hook, a vertical side frame pivotally connected intermediate its upper and lower edges to one side of said main frame, a horizontal upper frame overlying said main frame and pivotally connected along one side to said side frame, said upper frame being hinged along a median line thereof parallel to

5 said side frame, a latch pin on said upper frame, a latch mounted on said main frame and adapted to engage said latch pin for retaining said upper frame parallel to said main frame, means to move 10 said latch to disengage the same from said pin, a second side frame pivotally connected along its upper edge to said upper frame, a pendent link rigidly fixed to and depending from said upper frame adjacent said second side frame, an operating link pivotally connected to said main frame adjacent said second side frame, means to rotate said operating link about its pivot on said main frame, a short link pivotally connected at one end to said operating link at a pivot remote 15 from the said pivot thereof on said main frame and pivotally connected at the other end to said pendent link at a pivot below said upper frame, and means at the bottoms of said side frames to engage a load.

20
